COMBINATION TOOL

Daisy Strickland, Titusville, Fla.

Application November 28, 1952, Serial No. 323,021

1 Claim. (Cl. 132—75.5)

2

of each of the handles 12 are provided, adjacent the outer ends thereof with a pair of ears 14 in each case.

Pivoted to each pair of ears 14 by means of a pin 15 is an arcuately shaped tweezer arm 16 each of which is adapted to lie, when not in use, against the inner face of the associated arm or handle 12, as indicated in dotted lines at 17, for example, in Figure 1 but each of which may be extended outwardly as shown in full lines in Figure 1. The outer ends of each of the tweezer members 16 may be pointed or squared as shown, for example, in Figure 2 at 18.

In operation, it will be apparent that the blades 10 may be manipulated by means of the handles 12 in conventional manner to utilize the same as nail scissors. It will also be apparent that the outer surfaces 13 of the handles 12 may be utilized in conventional manner as nail files. Normally the tweezer members 16 will be pivoted upon the pins 15 to their dotted line position 17 as shown in Figure 4 but when it is desired to utilize the members 16 as a pair of tweezers, it is only necessary to extend the same to their full line position as shown in Figure 1 whereupon the handles 12 may be manipulated to thereby move the members 16 toward or away from each other as desired and it will be apparent that the end portions 18 of the members 16 may be utilized as tweezers in conventional manner.

While but one form of the invention has been shown and described herein, it will be readily apparent to those skilled in the art that many minor modifications may be made without departing from the spirit of the invention or the scope of the appended claim.

What is claimed is:

In a manicuring device including a pair of pivoted handles, a pair of arcuate tweezer arms hinged to the adjacent free ends of said handles to form a pair of tweezers when in extended position, said handles having concave inner surfaces adjacent their free ends, and said tweezer arms having their concave sides lying against the concave surfaces of said handles when in non-use position.

The present invention relates to a combination tool and it consists in the combinations, constructions and arrangements of parts herein described and claimed.

Generally there is provided a combined nail scissors, nail files and tweezers all included in a single instrument. The tweezers are so constructed that when not in use they fold against the inner sides of the handles of the scissors and the handles themselves are made in the form of nail files thus providing an ideal instrument for carrying by ladies in their pocketbooks.

It is accordingly an object of the invention to provide a novel combined nail file, nail scissors and tweezers.

Another object of the invention is to provide a device of the character set forth which is simple in construction, inexpensive to manufacture and yet effective and efficient in use.

Another object of the invention is to provide, in a device of the character set forth, novel pivoted tweezer members forming a part of the invention.

Other and further objects of the invention will become apparent from a reading of the following specification taken in conjunction with the drawing, in which:

Figure 1 is a plan view of an embodiment of the invention,

Figure 2 is a side elevational view thereof,

Figure 3 is an end elevational view of the device illustrated in Figures 1 and 2, and

Figure 4 is an enlarged fragmentary sectional view illustrating the manner of mounting a tweezer member forming a part of the invention.

Referring more particularly to the drawing, there is shown therein a combined nail file, nail scissors and tweezers comprising a pair of scissors blades pivoted, as indicated at 11 with a preferably accurate pivotal construction and each of the blades 10 having a bowed handle 12. The outer surfaces of the handles 12 are formed as nail files, as indicated at 13, and the inner faces
